UNITED STATES PATENT OFFICE.

CELESTIN GUSTAVE TINGRY, OF PORTLAND, OREGON.

DESIGN FOR A BADGE.

SPECIFICATION forming part of Design No. 24,179, dated April 9, 1895.

Application filed January 24, 1895. Serial No. 536,136. Term of patent 7 years.

To all whom it may concern:

Be it known that I, CELESTIN GUSTAVE TINGRY, a citizen of the United States, residing at Portland, in the county of Multnomah and

5 State of Oregon, have invented and produced a new and original Design for a Badge, of which the following is a specification.

Reference is to be had to the accompanying drawings, in which—

10 Figure 1 represents the obverse of a badge embodying my design; Fig. 2, the reverse of the same, and Fig. 3 is an edge view.

The leading feature of my design consists in the badge having the general configuration

15 of an elk's tooth, on the obverse of which is the representation of an elk drinking, said rep-

resentation being surmounted by a clock dial with the hands pointing to 11, the whole symbolizing an elk sacrificing to Bacchus at the appointed hour of 11. 20

The minor features are the division of both the obverse and reverse into upper and lower panels, separated by a scalloped line, and the ground on which the elk appears, the same being darkened and having a starry sky. 25

I claim—

The design for a badge herein shown and described.

CELESTIN GUSTAVE TINGRY.
